(57) **CLAIM**

We claim the ornamental design for a interdental cleaner, as shown and described.

DESCRIPTION

FIG. 1 is a top view of the interdental cleaner, showing our new design;

FIG. 2 is a bottom view of the interdental cleaner;

FIG. 3 is an isometric view of the interdental cleaner;

FIG. 4 is a left side-elevational view of the interdental cleaner, the right side-elevational view being the same; and,

FIG. 5 is a front view of the interdental cleaner, the rear view of the interdental cleaner being the same.

All broken lines are directed to environment and are for illustrative purposes only; the broken lines form no part of the claimed design.
